CLEMENT L. SCHOFIELD, OF GLENFIELD, PENNSYLVANIA, ASSIGNOR TO GLENFIELD MILLS, OF GLENFIELD, PENNSYLVANIA, A CORPORATION OF PENNSYLVANIA.

REVERSIBLE CUSHION OR BUFFER MAT.

Application filed November 14, 1919. Serial No. 333,053.

To all whom it may concern:

Be it known that I, CLEMENT L. SCHOFIELD, a citizen of the United States, residing at Glenfield, Allegheny County, Pennsylvania, have invented a new and useful Improvement in Reversible Cushion or Buffer Mats, of which the following is a full, clear, and exact description, reference being had to the accompanying drawing, forming 10 part of this specification, in which—

Figure 1 is a perspective view of a portion of a mat embodying my invention.

Figure 2 is a transverse section of the same, and

15 Figure 3 is a diagrammatic view showing the weave.

My invention has relation to reversible cushion or buffer mats and is designed to provide a mat which can be woven from some 20 fibrous material, such as cocoa yarn; which shall be perfectly reversible so that it may be used either side up; and which has a thick cushion body giving the mat considerable elasticity. Mats constructed in accordance 25 with my invention are specially useful as bowling alley mats, although they may be used for a variety of other purposes where a thick resilient mat is required.

The mat consists of upper and lower series 30 of parallel warp threads 2 and 3 which are separated from each other a distance a little less than the desired thickness of the finished mat. 4 designates warp or filler threads which are looped over both series of warp 35 threads in the manner clearly shown in Figures 2 and 3. This method of weaving gives, as will be readily seen, a double surface fabric alike on both sides, each of its

upper and lower surfaces being formed by the looped portions of the weft or filler 40 threads. In weaving this fabric may be woven in any desired lengths and then cut into the proper sizes for the finished mat. The cut lengths are then suitably stitched, as indicated at 5, so as to tie in the edge 45 loops. A binder of any suitable character, such as indicated at 6, is stitched entirely around the body.

It will be noted that the weft or filler threads lie thickly in the body of the fabric 50 thus giving it a considerable degree of resilient solidity and admirably adapting it for hard service.

In lieu of cocoa fibre, I may employ any other fibres or yarns known in the art and 55 suitable for mats of this character.

I claim:

As a new article of manufacture, a reversible cushion or buffer mat, comprising upper and lower separated parallel warp 60 threads and weft or filler threads looped over both series of warp threads and extending back and forth between the same, the looped portions of the weft or filler threads forming the upper and lower surfaces 65 of the mat which is alike on both sides, the loops of the weft or filler threads at the edges of the mat being stitched into the body of the mat, together with a surrounding binder secured to said body, said binder 70 further securing and binding said edge loops substantially as described.

In testimony whereof, I have hereunto set my hand.

CLEMENT L. SCHOFIELD.
